UNITED STATES PATENT OFFICE.

VICTOR WALTER SINTON, OF BELFAST, IRELAND.

CONVEYER.

1,210,994.

Specification of Letters Patent.

Patented Jan. 2, 1917.

Application filed June 10, 1916. Serial No. 102,976.

To all whom it may concern:

Be it known that I, VICTOR WALTER SINTON, a subject of the King of Great Britain, and resident of Belfast, Ireland, have invented certain new and useful Improvements in Conveyers, of which the following is a specification.

This invention relates to attachment and releasing devices for carriers, particularly adapted for use with portable conveyers wherein a wire, cable or the like is wound by means of drums from one station to another, and carries the goods in a suitable receptacle attached by a clip to the wire.

15 The construction and arrangement of the conveyer itself including the winding drums, the wire and so forth, form the subject of a separate patent application.

According to this invention the carriers 20 for the goods to be conveyed are provided with clips or grips for engaging with the wire, and a releasing device is provided for detaching the clips of the carriers automatically at the place where they are to be 25 received.

The invention is illustrated in the accompanying drawings, wherein:—

Figure 1 shows a carrier and clip in side elevation. Fig. 2 shows the same in plan. 30 Fig. 3 shows the rear end of the carrier drawn to a larger scale. Fig. 4 shows a supporting device at the rear end thereof to the same scale, as seen from above. Fig. 5 shows the clip to an enlarged scale in plan view. Fig. 6 shows the same in side elevation, and Fig. 7 shows the same in end elevation. Fig. 8 shows the automatic detacher for the clip in plan view. Fig. 9 shows the same in side elevation, and Fig. 40 10 shows the same in end elevation.

The carriers 1 may be made with rounded or pointed front ends as shown, and connected by links 2 to clips 3 whereby they are secured to the conveyer wire 4. The 45 carriers may hang or be dragged along the ground when supported by the front attachments 2 and 3 only, but it is preferred to provide also a simple form of support for the rear end of the carriers which will hold up 50 such ends upon the wire, but will release the same automatically when the clips 3 are detached by the automatic device hereinafter described. For this purpose each carrier 1 has a clip 5 attached to the top thereof at its 55 rear end, and formed with a diagonal slot

at 6 through which the wire 4 can pass when the carrier is set at an angle to the wire, but wherein the wire must hold so long as the axis of the carrier is in the same vertical plane as the wire. A projection 7 60 with an inclined face at the back of the clip 5 helps to hold the wire securely under running conditions as seen in the end view, Fig. 3. When the forward clip 3 is released however, and the carrier falls at its front 65 end, the rear end can set itself diagonally across the wire so that the wire at once escapes from the slot at 6, and the carrier is thus completely released.

The rear end of the carrier can be closed 70 in any convenient manner, for instance by a cap fitting by a bayonet joint, or as shown by means of a plate 8 pressed inward against a seating 9 by a screw 11 passing through a cross bar 10 which engages behind lugs 12, but can be turned to release 75 itself therefrom when the screw 11 is slackened.

A suitable form of clip 3 for engaging 80 with the wire 4 is shown in detail in Figs. 5 to 7. It has a pair of hardened steel gripping-jaws 13 pivoted on pins at 14 so that the arms of the jaws project toward the center line of the clip at an angle beyond the pivots, and behind a wedge-shaped head-piece 15. A spring 16 presses a collar 17 and a plate 18 with bent lugs thereon forwardly against projections 19 on the jaws, tending 85 to grip the jaws together, but the grip can be released by turning an arm 20 which projects at one side of the clip device and has a stem 21 wider in section in one direction than in the other, so that the turning of the stem will press back the plate 18 and release the spring tension upon the jaws 13. 90 Any other convenient release-mechanism 95 might be provided.

For attaching a carrier 1 to the wire, the jaws 13 of its clip are released by turning the arm 20 on the clip at right angles to 100 the line thereof, or the jaws may be held open by the finger and thumb pressing inward the tail pieces 22. The arm 20 and stem 21 may be omitted if it is not required to be possible to lock the jaws in the opened 105 position. Assuming the parts 20 and 21 to be provided, and the jaws to be opened thereby, the clip is then laid along the wire 4 from beneath, with the wire passing between the gripping jaws 13, and through 110

the groove at 23 in the head 15; the arm 20 is now turned until the spring 16 acting upon the somewhat oval stem 21 of the lever 20 will complete the motion, bringing 5 the gripping jaws 13 together on the wire and turning the lever arm 20 until it lies along the side of the clip, as in Figs. 5 and 6. The jaws 13 come together in a direction such that the pull of the wire 4 tends to cause them to grip more tightly 10 with a toggle action, so that there will be no risk of a clip releasing itself during use. The lever arm 20 might also be used for releasing the grip at the receiving end, but 15 it is preferred to provide an automatic mechanism for this purpose, such mechanism operating upon the projecting tail 20 ends 22 of the arms of the gripping jaws. Then the wedge-shaped head 15 of the clip 25 is caused to spread apart a pair of spring arms at the receiving station, the said arms being allowed to come together after passing the head, so as to permit strikers thereon to engage the tail ends 22 of the jaws, causing the jaws to open and allowing the 30 clips to drop off. In Figs. 6 and 7, the clip is shown as having a short link 40 hanging down therefrom to connect with the carrier by another link, instead of the longer curved link 2 being used as in Figs. 1 and 2.

The releasing device shown in Figs. 8, 9 and 10 has a pair of arms 26 pivoted at one end on a support 24 and drawn toward 35 one another at their other ends by a tension spring 25 acting between upright arms 27 attached to the arms 26. The arms are cranked inwardly at the end beneath the spring 25 to form rounded jaws 28 over 40 which the conveyer wire passes. The normal line of the wire in passing through the device is indicated by dotted lines 29 in Fig. 9. The device is in fact normally held in place on the frame to which it is attached in such a way that the inclined line 45 29 of the wire in passing between the two ends of the device, is approximately horizontal. The device may be supported for example by a cross piece at the end 24, and 50 by another cross piece clamped beneath screws 30 at the other end of the top plate 31. This top plate has a groove in its under-surface as indicated by the dotted lines 32, so as to permit the wire to pass within 55 it even when raised by a clip coming into the detaching position.

A vertical pin 33 on the top plate 31 carries toggle levers 34 connected by links 35 to pins 36 on the arms 26, so that the opening and closing movements of the two arms 60 will be equal and opposite. The arms 26 also carry tapered steel plates 37 adapted to be engaged by the wedge-shaped head 15 of each clip as it enters the detaching device.

In operation, when the nose 15 of a spring clip reaches the detaching device, it rides up over the rounded jaws 28 which are in contact, passing into the gap behind the same. It engages with the steel plates 37 70 pressing them apart so as to open the jaws 28 sufficiently widely to permit the hanging tail-piece 40 (or the link 2) of the clip to pass between the jaws. The clip holds the wire up so that it cannot drop between 75 the jaws while they are opened out. The clip is indicated by chain dotted lines in Fig. 8 in the position just before it becomes detached from the wire. The tail-piece or link 40 has passed clear beyond the jaws 80 28, and after a slight further forward movement the side faces of the nose of the clip will have passed the ends of the plates 37, allowing these to snap together against the tail-pieces 22 of the spring jaws 13, thus 85 releasing the spring jaws from the wire. The clip then falls away from the wire, there being nothing beneath the detacher to impede its movement, and the jaws 28 come together beneath the wire before it 90 can fall through between the same. The detacher is therefore ready to operate on and release the next clip which comes along. The detacher as illustrated might be considerably modified without departing from 95 the scope of the invention, and its construction is shown by way of example only.

Detaching or releasing devices for the clips can be placed in any desired position in connection with the conveyer. Generally 100 one at the receiving station to detach the full carriers and one at the return end of the transmitting station to detach the returned empty carriers will be all that are required.

The carriers 1 need not necessarily have the shape shown in Figs. 1 and 2. The carriers are preferably made rounded in section and of light steel which will be strong enough to cause the carriers to glance off 110 any hard obstructions, and to deflect bullets and the like which do not impinge too directly against the surface.

Having thus described my invention what I claim as new and desire to secure by Letters Patent, is:-

1. An attachment device for a wire conveyer, comprising a block with a tapered nose adapted to coöperate with a releasing mechanism, a pair of jaws behind said tapered nose, said jaws being pivoted on the block and having tail pieces projecting laterally therefrom for coöperation with the releasing mechanism, a spring and a member pressed forward thereby normally holding 120 said jaws close together to grip the conveyer wire, a handle and a transverse bar in connection therewith adapted when the handle is moved into one position to press back the member aforesaid against the action of the 125 member aforesaid against the action of the 130

spring, and to release the said jaws, and means for connecting to the clip the article to be carried thereby.

2. A wire-engaging and releasing mechanism for a conveyer, comprising a clip with a tapered nose, a pair of wire-engaging jaws pivotally supported on said clip and having tail pieces which normally project laterally from said clip behind the nose, a spring device normally pressing together the engaging faces of said jaws, means for attaching to said jaws the article to be carried by the clip, a pair of stationary releasing jaws with means for supporting them at the position where the clip is required to be detached from the conveyer wire, a spring device normally drawing together the releasing jaws in such manner that they form a surface over which the conveyer wire will pass, cheeks on said releasing jaws adapted to be pressed apart by the tapered nose of the clip, and to approach one another again behind the tapered nose under the action of the spring device to press back the jaws of the clip whereby the same is released from the conveyer wire.

3. The combination with a conveyer having a traveling wire, of a clip for securing articles to said wire, said clip having a tapered nose, a wire engaging mechanism and a tail piece adapted to serve as an attachment for the articles to be carried by the clip, and a releasing device comprising a pair of releasing jaws with means for drawing them together and means for supporting them at the place where the clips are to be released from the conveyer wire, said releasing jaws having rounded faces over which the conveyer wire and also the nose of a clip will ride, cheeks on said releasing jaws adapted to be pressed apart by the nose of a clip, and to hold said releasing jaws separated to such an extent that the tail

piece of a clip can pass between the releasing jaws, said cheeks being adapted after the nose of a clip has passed the same, to operate upon the wire-engaging mechanism of the clip and to release the same from the wire.

4. In a conveyer the combination with the conveyer wire of a clip with means thereon for engaging with the wire and a tail piece extending rearwardly therefrom, a carrier in the form of a casing attached to said tail piece, a projection on the carrier near to the rear end thereof formed with a diagonal slot and an undercut space beneath the same, whereby the rear end of said carrier will hang upon the wire when the carrier has been turned at an angle to the wire in order to pass the same through the diagonal slot before the clip is secured to the wire in order to hold the carrier along the same, and means for releasing the clip from the wire at its destination, whereby when the clip is allowed to fall, releasing the forward end of the carrier, the carrier is allowed to turn sufficiently to permit the wire to pass out of the diagonal slot in said projection thereby automatically releasing the carrier completely from the wire.

5. In a conveyer the combination with the conveyer wire of a clip with means thereon for engaging with the wire, automatic means for disengaging the clip from the wire at the destination, a carrier attached to said clip, and a projection on said carrier with a diagonal slot in the top thereof communicating with an undercut aperture whereby the carrier can be hung upon the wire by causing the wire to pass through the diagonal slot, while the carrier is at an angle to said wire, then turning the carrier along the wire, and engaging the clip at its forward end therewith.

VICTOR WALTER SINTON.
